CLAIM

The ornamental design for a sponge head for a hand-held cleaning utensil, as shown and described.

DESCRIPTION

FIG. 1 is a bottom plan view of the present invention.

FIG. 2 is a right side elevational view of the present invention.

FIG. 3 is a rear elevational view of the present invention.

FIG. 4 is a rear front perspective view of the present invention; and,

FIG. 5 is a top plan view of the present invention.

Certain views have been omitted as duplicative. The left side elevational view of the present invention is a mirror image of the right side elevational view shown in FIG. 2. To the extent any surface is not shown or discernible from the other views shown in the figures, it is to be understood that that surface is flat and includes no surface ornamentation.
